UNITED STATES PATENT OFFICE.

SIMON ROSS, JR., OF NEWPORT, KENTUCKY.

LEATHER-SPLITTING MACHINE.

SPECIFICATION forming part of Letters Patent No. 378,179, dated February 21, 1888.

Application filed August 18, 1886. Serial No. 211,193. (No model.)

To all whom it may concern:

Be it known that I, SIMON ROSS, Jr., of Newport, Campbell county, Kentucky, have invented certain new and useful Improvements 5 in Leather-Splitting Machines, of which the following is a full, clear, concise, and exact description, reference being had to the drawings accompanying and forming a part hereof, in which—

10 Figure 1 is a plan view. Fig. 2 is a front elevation. Fig. 3 is a section on line xx , Fig. 1. Fig. 4 is a section on line yy , Fig. 1. Fig. 5 is a section on line zz , Fig. 4. Fig. 6 is a top view of the movable arms which carry the 15 lower feed-roll detached. Fig. 7 is an edge view and plan of the splitting-knife. Fig. 8 is an end and plan view of the eccentric-bolt.

My invention belongs more especially to that class of leather-splitting machines the 20 object of which is to split a piece of scrap-leather to a hinge at one side, so that by spreading the flaps or parts of the split piece into the same plane a flat piece of leather may be formed which will have twice the area and 25 one-half the thickness of the original unsplit piece. Such split pieces of scrap-leather are shown and referred to in Letters Patent to Jeremiah M. Watson, No. 213,364, dated March 18, 1879.

30 While my present invention is particularly adapted for splitting pieces of leather in the manner described, yet it may by very slight adjustment be used for the entire severing of the leather into layers having any proportionate thickness to the original unsplit piece.

The pieces of leather which are to be split vary in thickness, and different parts of the same piece vary from each other in thickness; but it is desirable, if the leather is to be split 40 centrally at one point, that it be split centrally throughout, and to accomplish this the edge of the knife must be in the center of the space between the feed-rolls, and if this space changes, by reason of a change in the thickness of the 45 leather passing between the rolls, the knife must automatically change its position accordingly.

In the following description of my machine shown in the drawings which embodies my 50 invention, I have used like letters of reference to indicate like parts throughout.

The stationary frame of the machine is represented at A. This frame may be of any shape. I find the shape shown a convenient one. B is the shaft of the upper feed-roll, 55 which is journaled in the frame A, and carries at one end the corrugated feed-roll C and at the other a gear, D, and the belt-pulleys E, by which power is applied. Directly beneath the shaft B, I arrange a shaft, F, which is 60 journaled in movable arms a b , which are fast on the short rocker shaft d , journaled in the frame A. The shaft F carries at one end the corrugated feed-roll G and at the other a gear, H, which meshes with the gear D on shaft B, 65 and by means of which the shaft F is driven.

Underneath the bearing of the shaft F is placed a spiral spring, J, secured to the frame A or resting thereon and designed to support the movable arms a b and hold the lower 70 feed-roll up against or near to the upper feed-roll. A movable knife-block, K, is dovetailed vertically in the frame A, in order that it may slide upward and downward therein. This block is provided with a projection, L, to the 75 top of which the knife is bolted by means of a screw-bolt, f, which passes through a slot in the knife, thus admitting of its lateral adjustment relative to the feed-rolls. At one side of the block a strip, h, is placed on which the 80 adjusting-screws j bear. This arrangement enables the wear of the block to be taken up. The rear face of the block is connected, by means of an eccentric-bolt, s, (see Fig. 8,) with a block, k, which is pivoted at its upper end to 85 the movable arm b . A set screw, m, is set in the boss on the rear face of the knife-block and bears against the eccentric-bolt, serving to keep it from turning when the machine is in use.

The purpose of the eccentric is the adjustment of the knife vertically, so that it may be set nearer to one of the feed-rolls than to the other. This may be easily accomplished by loosening the set-screw k and turning the eccentric. The outer face of the knife-block also serves as a guide for the unsplit edge of the leather after it passes the splitting-knife, the distance between the inner end of the shaft and the face of the block serving to gage the 90 width of the unsplit margin which it is desired to leave as a hinge.

In front of the feed-rolls I provide a gage, M, which consists of a flat piece of metal provided with a spindle or shank, p, projecting at right angles thereto, and which is inserted 5 in a hole or socket in the arm r, which projects from the frame A. By means of this spindle the gage may be adjusted relatively to the line of the inner end of the splitting-knife.

- 10 The operation of the machine will be readily understood. A piece of leather, which has been first trimmed to a straight edge at one side, is placed with the straight edge against the guide M and fed between the feed-rolls, 15 which seize it and force it onto the splitting-knife, from which it passes split to a hinge at the edge. When the leather enters the feed-rolls, it forces the lower feed-roll downward against the pressure of spring J, thus moving 20 downward the arms a b and carrying the knife and its block downward a distance proportionate to the downward movement of the lower feed-roll. If it is desired to split the leather centrally, the knife should move downwardly 25 one-half the distance of the lower feed-roll, which obviously will result when the knife-block is attached to the arm b at a point just midway between the axis of the lower feed-roll and the axis of the rocker-shaft d.
- 30 A set-screw, A', (see Fig. 4,) is set in the frame A, and operates against the pressure of spring J to bear down the arms a b, and thus regulate the pressure of the feed-rolls on the stock.
- 35 A feed-table upon which to rest the stock before it enters the feed-rolls may be secured

in any suitable manner to the stationary frame in front of these rolls, if desired. The knife may also be so mounted on its support as to admit of adjustment nearer to or farther from 40 the face of the knife-block K, and thus change the width of the unsplit margin. I have not shown such an adjustment, because in practice the width of the unsplit margin is substantially the same for all ordinary thicknesses 45 of scrap-leather, and also because any competent mechanic can easily arrange the knife with such an adjustment should it be deemed necessary.

What I claim is—

1. In a leather-splitting machine, the combination, with a pair of feed-rolls and a movable support for one of the said rolls, of a splitting-knife, a movable knife-block, a link, as k, pivotally attached to said movable support, 55 and an eccentric-bolt by which the said link and knife-block are connected, whereby the said knife may be adjusted relatively to the movable feed-roll, substantially as set forth.

2. The combination, with the fixed feed-roll 60 C and its shaft B, of the movable feed-roll G, its shaft F, the movable support in which the said shaft F is journaled, the spring J, for pressing the movable rolls toward the fixed roll, the splitting-knife having its edge parallel to the axes of the said rolls, and the movable knife-block connected with the said movable support, substantially as set forth.

SIMON ROSS, JR.
